UNITED STATES PATENT OFFICE.

HARRY S. CLEVELAND, OF FARIBAULT, MINNESOTA, ASSIGNOR TO NELLIE R. CLEVELAND,
OF FARIBAULT, MINNESOTA.

ICE-PROTECTOR.

No. 862,052.

Specification of Letters Patent.

Patented July 30, 1907.

Application filed December 12, 1905. Serial No. 291,494.

To all whom it may concern:

Be it known that HARRY S. CLEVELAND, a citizen of the United States, residing at Faribault, in the county of Rice and State of Minnesota, has invented 5 new and useful Improvements in Ice-Protectors, of which the following is a specification.

My invention relates to refrigerators and the like, and has particular relation to a device to be placed within the ice chamber over the ice whereby the ice 10 is protected from rapid melting &c.

The object of the invention is to provide a device of the above type which will be strong and durable and yet capable of being readily removed from one ice chamber to another, the construction being such that 15 while the ice is fully protected, there will be no interruption to the proper circulation of air necessary to protect the contents of the refrigerator.

With this and other objects in view, the invention comprises a frame, the sides and ends of which have 20 coverings of insulating material, such as asbestos, mineral wool or the like, the said insulating material covering all of the four sides of the frame excepting a narrow strip at the lower edges, the said narrow strip at the lower edges being left open to serve as outlets 25 for the cooled air. A lid or cover is hinged to the top of the said frame, and this lid or cover has a covering of insulating material, such as asbestos, mineral wool, or the like, an opening being formed in the center thereof for the admission of air. At the front edge of 30 the lid or cover an eye is fastened, with which engages a hook carried by the lid, or door, of the refrigerator, whereby, when the said lid or door of the refrigerator is raised, the lid or cover of the ice protector is also caused to rise.

35 In the drawings Figure 1 is a perspective view of a refrigerator, the front part thereof being removed to show the practical application of my invention. Fig. 2 is a sectional view of the ice protector. Fig. 3 is a sectional view of a modification.

40 The invention is designed more especially for use in connection with that class of refrigerators and the like, wherein the ice chamber is composed of a shelf like structure, having a metallic lining to the bottom and side walls, a space being left between the said side walls 45 of the shelf like structure and the walls of the refrigerator through which the air circulates. In such types of refrigerators and the like, the ice is usually placed upon the bottom of the ice chamber, and as there is no means provided for controlling the circulation of 50 the air, there is constantly a flow of air toward all portions of the ice. It has been found by experiment, that with a protector or covering for the ice of sufficient size to be fitted over the ice and leave a space between

the walls of the protector and the ice, that a cold zone will be formed in said space, such cold zone acting 55 upon the air admitted to said zone and immediately purifying it. In a protector of this kind it is necessary, of course, to provide an inlet for the admission of the warm or impure air and an outlet for the purified air, and also provision must be made whereby there is no 60 possibility of the air or moisture being admitted within the ice protector except through the air admission opening.

In the accompanying specification and drawing I have described and illustrated the details of my invention.

1 designates a refrigerator provided with the usual lid or cover B, and ice chamber C.

The ice protector 1 have designated generally as 1, and consists of an upper and lower rectangular frame 70 2—3, composed of thick wires, and these two frames 2—3 are joined together by vertically arranged thin wires 4, and transversely through the said thin wires 4 are arranged similar wires 5, the whole forming a hollow rectangular frame of heavy upper and lower 75 wires, and sides and ends of intermeshing thin wires. A covering 6 of insulating material, which may be asbestos, mineral wool or the like is placed around the sides and ends of the hollow framework so as to extend from the upper heavy wires 2 down to within a short 80 distance of the lower heavy wires 3, leaving an open space 7 at the bottom of the framework. This insulating material 6 has openings 15' formed in its top, and is held in position upon the framework by means of binding wires 8.

9 designates a lid or cover which is connected to the upper portion of the framework 1 by means of hinge 10. This lid or cover is composed of a frame of heavy wires 11, and longitudinally and transversely thereof extends thin wires 12—13. A covering 14 of insulating material is placed within the meshes formed by the wires 12—13, the said covering being of a size to completely 90 cover the said lid or cover 9. At the center of the covering 14 an opening 15 is formed.

16 designates an eye centrally located upon the front 95 edge of the lid or cover, and a hook, 17 or the like is located upon the lid or cover B of the refrigerator in a position whereby it can engage the said eye 16.

In the practical application of my invention, the protector is placed over the ice in the ice chamber, the hook of the lid or cover is engaged with the eye of the lid of the protector, and both are then closed. The warm and impure air from the lower portion of the refrigerator ascends through the space between the side walls of the shelf like structure and the walls of the 105 refrigerator and enters the ice protector through the

upper openings 15' in the sides of the ice protector and the central opening 15 in the lid or cover. As soon as this air enters the protector it is cooled and purified and descends through the cold zone and out through the 5 lower openings and thence downward into the lower part of the refrigerator. This circulation is shown in Fig. 1 of the drawings by means of arrows.

When it is desired to have access to the protector for the purpose of replenishing the ice or for cleaning &c., 10 the lid or cover of the refrigerator is raised, and by means of the hook and eye engagement of the said refrigerator lid and the lid of the protector, both will be opened together.

Various modifications of the above described structure may be provided. For instance, when it is desired to use the protector in connection with a refrigerator the ice chamber of which is provided with front doors, instead of the top lid, the protector's side would be hinged as indicated by dotted lines in Fig. 1, and 15 20 an eye would be placed thereon for engagement with a hook upon one of the doors, so that by opening the said doors the side of the protector also would be opened.

Another modification of my invention is shown in Fig. 3 of the drawings. In this form of the invention, 25 the frame is composed of sheet metal, designated by reference letter A'. The lower portion of this sheet metal frame A' is provided with openings 19, and a layer of insulating material 6' is passed around the outer side of the frame, the said insulating material being arranged on the said frame so that its lower edge 30 will extend down in close proximity to the opening 19 in the lower portion of the frame. Openings 24 are formed in the upper part of the frame, which form air inlets. B' designates an outer frame of sheet metal, 35 which is placed around the insulating material, and is designed to hold the said insulating material in place upon the frame A'. The lid or cover in this form of the invention is also composed of sheet metal having the insulating material thereon, and an additional 40 layer of sheet metal is placed over the said insulating

material, so as to make a lid structure composed of the two layers of sheet metal with the insulating material therebetween, and through these a central opening is formed.

While I have shown the device as applied to household refrigerators, it will be understood that with minor changes which fall well within the scope of my invention, it could be adapted for use in connection with ice boxes, butcher coolers and the like.

I claim—

1. An ice protector consisting of a metal frame having upper air inlets and lower air outlets, an insulating material partially covering said metal frame, the upper portion of said insulating material being provided with openings which register with the upper openings in the metal frame, the lower edges of said insulating material terminating slightly above the lower openings in the metal frame, means for retaining said insulating material upon the metal frame, and an insulated lid or cover hinged to said metal frame, said lid or cover being provided with a central 55 60 opening.

2. An ice protector consisting of a framework of heavy wires and thin wires; an insulating material partially covering said framework to leave openings at the lower portion thereof; a lid or cover of thick and thin wires, and 65 an insulating material covering said lid or cover, said insulating material being provided with a central opening.

3. An ice protector consisting of a framework of upper and lower heavy wires; thin wires arranged longitudinally and transversely within said frames to form sides and ends of intermeshing wires; an insulating material covering said intermeshing wires, said insulating material being provided with perforations at its upper portion and being so arranged that lower openings are left in the frame; a lid or cover for the said frame work hinged to the upper portion of the frame, said lid or cover being composed of a frame of heavy wires and longitudinally and transversely arranged thin wires crossing said frame, and an insulating covering for said lid or cover, the said insulating covering being provided with a central opening.

In testimony whereof I affix my signature, in presence of two subscribing witnesses.

HARRY S. CLEVELAND.
